HARRY L. PELZER, OF HIGHLAND, INDIANA, AND EUGENE C. HERTHEL, OF CHICAGO,
ILLINOIS, ASSIGNORS TO SINCLAIR REFINING COMPANY, OF NEW YORK, N. Y., A
CORPORATION OF MAINE

APPARATUS FOR CRACKING HYDROCARBONS

Application filed December 12, 1928. Serial No. 325,413.

- This invention relates to the cracking of higher boiling hydrocarbon oils, such as gas oil, for the production of lower boiling oils, such as gasoline or gasoline-containing oils, by distillation under superatmospheric pressure. More particularly the invention relates to improvements in apparatus for carrying out pressure distillation cracking operations.
- Pressure distillation cracking operations have been well known and widely practiced for many years. In many of such cracking operations it is customary to circulate a high boiling oil through a heating zone, in which it is heated to a cracking temperature, to a vaporizing zone from which vapors of the cracked oil, including vapors of the desired lower boiling oil, are taken off under superatmospheric pressure. In one such known type of operation, only oil free from unvaporized components of oil which has once passed therethrough is circulated through the heating zone. In another, unvaporized oil is maintained in circulation through the heating zone. A process embodying the features of the two types of operation just mentioned is described in an application of Eugene C. Herthel, filed January 12, 1928, Serial No. 246,262 now U. S. Patent No. 1,721,779, and the apparatus of the present invention is of special value and application in connection with the improved process described therein. In the process described in the Herthel application, above noted, an initial charge of oil is brought to cracking conditions of temperature and pressure, the higher boiling oil is circulated and recirculated from the vaporizing zone through a heating zone in which it is heated to a cracking temperature and back to the vaporizing zone, and vapors of the cracked oil are taken off from the vaporizing zone and raw oil is supplied to the higher boiling oil circulating through the heating zone as the operation continues. After a substantial amount of cracked oil has been taken off and before the oil circulating through the heating zone becomes saturated with pitch, recirculation of unvaporized oil from the vaporizing zone to the heating zone is stopped, the circulation of raw oil through the heating zone being continued and vapors of the cracked oil being taken off from the vaporizing zone until a further substantial amount of cracked oil has been taken off. At the same time that the recirculation of unvaporized oil from the vaporizing zone through the heating zone is stopped, or somewhat later, discharge of unvaporized oil from the vaporizing zone is begun to prevent excessive accumulation of unvaporized oil in the vaporizing zone. The vapors taken off from the vaporizing zone during both periods of operation are subjected to a refluxing operation from which higher boiling components of the vapors are recirculated as reflux condensate through the heating zone.
- The present invention provides an improved apparatus which may be used to particular advantage in connection with a process combining certain of the features of the two known types of operation as above described and when employed in this connection permits the advantages of each of these types of operation to be obtained to a maximum degree while eliminating the disadvantages of both.
- The apparatus of the present invention provides for uniform distribution of the heating effect on the oil heating surfaces and for uniform distribution of the oil being heated over these heating surfaces, when being operated either with recirculation of unvaporized oil through the heating zone or with recirculation of reflux condensate only, to as great an extent as these objectives are accomplished in bulk oil cracking operations wherein a large body of oil is maintained at a substantially uniform cracking temperature in a bulk supply drum by circulating it from the bulk supply drum through a battery of heating tubes connected in multiple and back to the bulk supply drum. The apparatus of the invention also provides for prolonged exposure of the oil being treated to the more severe cracking conditions advantageous to the production of gasoline or gasoline-like oils of high anti-knock character. It is a further advantage of the apparatus of the invention that it is adapted for the maintenance of the apparatus.

nance of a higher velocity of circulation of the oil being treated over the heating surfaces than is ordinarily maintained in bulk oil cracking operations where unvaporized residual oil is repeatedly circulated through the heating zone.

One form of apparatus embodying the invention is illustrated in the accompanying drawing and will be further described in connection therewith, but it is intended and will be understood that this further detailed illustration is for the purpose of exemplification and that the invention is not limited thereto. The accompanying drawing diagrammatically and conventionally represents a pressure still system, in elevation and partly in section, embodying the invention.

Referring to the drawing, the pressure still system illustrated comprises a battery of heating tubes 2 arranged in the heating flue of the furnace 3, the vaporizing drum 4, circulating connections 5, 6 and 7 including a pump or other suitable forcing means 8, these connections and forcing means being arranged for circulating oil from the vaporizing drum upwardly through the heating tubes and back to the vaporizing drum, a valve 9 for closing the connection between the vaporizing drum 4 and the inlet side of the forcing means 8, a reflux tower 10 with vapor connection 11 and reflux return connection 12 to the still proper, a connection 13 for introducing raw oil into the reflux tower 10, a condenser 14, a receiver 15, and a connection 16 for discharging unvaporized oil from the vaporizing drum 4.

The battery of heating tubes 2 are shown as, and may to advantage be, arranged in accordance with the improved heater construction described and claimed in an application of Harry L. Pelzer, filed June 17, 1927, Serial No. 197,035, now U. S. Patent No. 1,774,291. This battery of tubes is made up of a series of banks of vertically arranged heating tubes with connections for circulating oil from the top of the first bank to the bottom of the second bank, from the top of the second bank to the bottom of the third bank and so on. These connections joining the upper end of each bank of heating tubes, except the last, with the lower ends of the successive banks, are arranged externally of the heating flue in which the battery of heating tubes is arranged. The individual banks of heating tubes are composed of a plurality of heating tubes with headers at their upper and lower ends arranged to connect the heating tubes of each separate bank in multiple. The circulating connections 5 and 6 from the bulk supply drum connect with the lower end of the first bank of heating tubes in the series, and the circulating connection 7 to the bulk supply drum connects with the upper end of the last bank of heating tubes in the series. The connection 5 for circulating oil from the

vaporizing drum 4 to the heating tubes 2 opens upwardly into the vaporizing drum below the normal liquid level therein.

The valve 9 proper is arranged at the upper end of this connection. The form of valve illustrated, which is particularly advantageous, comprises a conical closure member arranged to separate the circular opening between the vaporizing drum 4 and the circulating connection 5. For raising and lowering the conical member 9 an operating extension 24 is attached thereto and carried through the wall of the vaporizing drum through a stuffing box 25 arranged above the normal liquid level, the operating extension passing upwardly through the vaporizing drum and in the vapor space therein. The operating extension 24 is, with advantage, rigidly fixed to the closure member 9 so that all parts of the valve mechanism exposed to high temperatures and hot oil in the still are of maximum simplicity. The reflux return connections 12 open into circulating connection 5 between valve 9 and the intake side of the forcing means 8. With this arrangement the change from circulation through the heating tubes of admixed reflux condensate and unvaporized oil from the vaporizing drum, to circulation through the heating tubes of reflux condensate without admixture of unvaporized oil from the vaporizing drum, or vice versa, can be made simply by closing or opening, respectively, valve 9.

Connection 17 is provided for discharging the distillate product and connection 18 for discharging uncondensed vapors and gases from the receiver 15. Pressure in the system may be maintained or regulated by means of valve 19 in the vapor line 20 between the reflux tower and the condenser 14 or by means of suitable valves arranged beyond the condenser or receiver. Connection 21 is provided for initially charging the still at the beginning of the run and for pumping out the still at the end of the run. To provide for complete draining of the battery of heating tubes connection 26 may be arranged with separate valved connections to each of the lower headers. Connection 22 is provided for supplying cool oil, for example, cool raw oil to be supplied to the still system, to or through the bearings of the forcing means 8. One form of circulating pump, or forcing means, particularly adapted for use in conjunction with the apparatus of the present invention is a positive displacement type of pump such as that illustrated in the applications of Thomas de Colon Tifft, Serial No. 197,209, filed June 7, 1927 now U. S. Patent No. 1,701,198, and Serial No. 197,210, filed June 7, 1927, now U. S. Patent No. 1,701,166, which are especially adapted to maintain a high rate of circulation through the oil heater.

Connections 23, including suitable forcing means, are provided for recirculating over

the heating tubes a portion of the heating gases which have passed thereover, as described in Letters Patent No. 1,574,546 and 1,574,547 issued to the Sinclair Refining Company February 28, 1926, on applications of John E. Bell.

As an example of one method of operating the pressure still or pressure still system illustrated in the drawing, the still may be initially charged with about 6000 to 8000 gallons of gas oil with the valve 9 open, the pump 8 started and the furnace 3 fired. As soon as the pump 8 is started, raw oil may be forced through connection 22 into the bearings of the pump at a rate of about 250 gallons per hour. As the still charge is heated, any water or very light hydrocarbons are vaporized and permitted to escape through the vapor line 20. After a period of about four to five hours, valve 19 may be closed and the still gradually brought to operating temperature and pressure. When the pressure in the system reaches, for example 100 to 300 pounds per square inch, the valve 19 may be gradually opened and regulated to maintain the desired predetermined pressure in the system. At about the same time the introduction of raw oil through connection 13 into the upper end of the reflux tower 10 may to advantage be started and the rate of introduction regulated to maintain the desired temperature at the top of the reflux tower, for example 550° F. The rate at which raw oil is introduced into the upper end of the reflux tower 10 may reach 2000 gallons per hour or more. Additional raw oil, for example, to maintain the charge of oil in the vaporizing drum 4 may be supplied through connection 22. The total rate at which raw oil is supplied may reach 2500 gallons per hour or more. The vapors of the cracked oil escaping uncondensed from the reflux tower 10 through connection 20 will be condensed in the condenser 14 from which the resulting condensate is discharged into the receiver 15. During this first period of operation in which vapors are taken off from the still, the charge of oil in the still is circulated and recirculated through the heating tubes 2 from and to the vaporizing drum 4. The oil travels through the heating zone in a succession of passes in each of which the relation between the circulation of the oil and the flow of the heating gases is the same. The circulating oil is thus passed again and again through the heating zone while the arrangement is such that the heating tubes are afforded a maximum of protection against overheating, general or local. The temperature of the oil as it is discharged from the last bank of heating tubes in the heating furnace may be somewhat in excess of the temperature corresponding to the pressure at that point, that is the oil may be somewhat superheated as it is discharged from the battery of heating tubes. Before the circulating still

charge becomes saturated with pitch or pitch-like constituents, for example by the time the distillate taken off amounts to 15%, or somewhat more, of the total raw oil including the initial charge supplied to the operation, the valve 9 should be gradually closed. The first period of operation, after the still is brought to operating conditions of temperature and pressure, may approximate two to three hours or longer. The closing of the valve 9 should be very slow to permit gradual self-adjustment of the operation to the change in operating conditions; for example, complete closure of the valve 9 may require an hour. When the valve 9 is completely closed, but preferably not until then, the discharge of unvaporized oil from the vaporizing drum 4 should be commenced and regulated, for example, to maintain a constant level within the vaporizing drum. During the second period of operation, after the valve 9 is closed, the oil mixture circulating through the heating tubes 2 includes only admixed reflux condensate and unvaporized raw oil. This second period of operation may last from 20 to 200 hours or longer depending upon the particular stocks under treatment and the particular products desired.

As the operation terminates, the fires may be first drawn and the valve 9 then gradually opened over a period of from one-half to one hour, while the introduction of raw oil through connection 13 is continued, as described above.

We claim:

1. A pressure still system comprising a vaporizing drum, a series of banks of heating tubes, said banks comprising a plurality of heating tubes connected in multiple, connections arranged to join said banks of heating tubes in series, a connection opening into the vaporizing drum from below the normal liquid level therein for circulating oil from the vaporizing drum to the heating tubes, a forcing means in said last mentioned connection, a valve adapted to close said last mentioned connection between the vaporizing drum and the forcing means, a connection for transferring oil from the heating tubes to the vaporizing drum, a reflux tower and a vapor connection between the same and the vapor space of the vaporizing drum, and a reflux return connection from the reflux tower opening into said connection for circulating oil from the vaporizing drum to the heating tubes between said valve and the heating tubes.

2. A pressure still system comprising a vaporizing drum, a series of banks of heating tubes, said banks comprising a plurality of heating tubes connected in multiple, connections arranged to join said banks of heating tubes in series, a connection opening into the vaporizing drum from below the normal liquid level therein for circulating oil from the vaporizing drum to the heating tubes, a forc-

ing means in said last mentioned connection, a valve adapted to close said last mentioned connection between the vaporizing drum and the forcing means, a connection for transferring oil from the heating tubes to the vaporizing drum, a reflux tower and a vapor connection between the same and the vapor space of the vaporizing drum, and a reflux return connection from the reflux tower opening into said connection for circulating oil from the vaporizing drum to the heating tubes between said valve and said forcing means.

3. A pressure still system comprising a vaporizing drum, a series of banks of heating tubes, said banks comprising a plurality of heating tubes connected in multiple, connections arranged to join said banks of heating tubes in series, a connection opening upwardly into the vaporizing drum below the normal liquid level therein for circulating oil from the vaporizing drum to the heating tubes, a forcing means in said last mentioned connection, a valve arranged at the upper end of said last named connection and an operating extension therefor extending upwardly through the vaporizing drum and through the vapor space within the same and passing through the walls of the vaporizing drum above the normal liquid level therein, a connection for transferring oil from the heating tubes to the vaporizing drum, a reflux tower and vapor connection between the same and the vapor space of the vaporizing drum, and a reflux return connection opening into said connection for circulating oil from the vaporizing drum to the heating tubes between said valve and the heating tubes.

4. A pressure still system comprising a vaporizing drum, a series of banks of heating tubes arranged in a heating flue, said banks comprising a plurality of heating tubes connected in multiple, connections between the upper ends of the banks of heating tubes, except the last, in such series and the lower ends of the successive banks, said connections being arranged externally of the heating flue in which the heating tubes are arranged, a connection opening into the vaporizing drum below the normal liquid level therein for circulating oil from the vaporizing drum to the lower end of the first bank of heating tubes in said series, a forcing means in said last named connection, a valve adapted to close said last named connection between the forcing means and the vaporizing drum, a connection from the upper end of the last bank of heating tubes in said series to the vaporizing drum, a reflux tower and vapor connections between the same and the vapor space of the vaporizing drum, and a reflux return connection from the reflux tower opening into said connection for circulating oil from the vaporizing drum to the heating tubes between said valve and the heating tubes.

5. A pressure still system comprising a

vaporizing drum, a series of banks of heating tubes arranged in a heating flue, said banks comprising a plurality of heating tubes connected in multiple, connections between the upper ends of the banks of heating tubes, except the last, in such series and the lower ends of successive banks, said connections being arranged externally of the heating flue in which the heating tubes are arranged, a connection between the lower end of the first bank of heating tubes in the series and the vaporizing drum opening into the vaporizing drum below the normal liquid level therein, a forcing means in said last named connection arranged to circulate oil from the vaporizing drum to the heating tubes, a valve adapted to close said last named connection between the vaporizing drum and the forcing means, a connection between the upper end of the last bank of heating tubes in the series and the vaporizing drum, a reflux tower and vapor connections between the same and the vapor space of the vaporizing drum, a reflux return connection from the reflux tower opening into said connection for circulating oil from the vaporizing drum to the lower end of said first bank of heating tubes between said valve and the heating tubes, a firebox communicating with one end of said heating flue and a stack flue with the other end thereof, said heating tubes being so positioned in said heating flue with respect to the firebox and with respect to the heating tube connections that the first bank of heating tubes in said series will contact first with heating gases passing through the heating flue.

In testimony whereof we affix our signatures.
